UNITED STATES PATENT OFFICE.

JOHN W. FOSTER, OF WESTFIELD, MASSACHUSETTS, ASSIGNOR TO THE
FOSTER MACHINE COMPANY, OF SAME PLACE.

STOP-MOTION FOR SPOOLING-MACHINES.

SPECIFICATION forming part of Letters Patent No. 499,665, dated June 13, 1893.

Application filed August 6, 1892. Serial No. 442,332. (No model.)

To all whom it may concern:

Be it known that I, JOHN W. FOSTER, of Westfield, county of Hampden, State of Massachusetts, have invented an Improvement in Stop-Motions for Spooling-Machines, of which the following description, in connection with the accompanying drawings, is a specification, like letters and figures on the drawings representing like parts.

10 This invention has for its object to improve and simplify stop motion devices used in spooling machines.

United States Patent No. 404,831, granted to me June 11, 1889, shows a form of stop motion wherein a tipping lever under the control of a drop wire is, when acted upon by a drop wire, moved longitudinally to effect the stopping of that drum which rotated the spool to which the said yarn was being supplied. In 15 20 25 30 35 40 45 50 55 60 65 70 75 80 85 90 95 100

said patent the tipping lever was carried by a sliding bolt, and with said bolt there was combined devices for unlocking a brake to act against the driving drum.

In the present invention, the tipping lever, 25 30 35 40 45 50 55 60 65 70 75 80 85 90 95 100

when acted upon by the ratchet wheel, a yarn having been broken, acts on the brake lever and causes it to act as a brake against the driving drum, preferably in the form of a shell roll such as common to United States Patent No. 459,039, and instantly stop the rotation of that driving drum or shell roll.

Figure 1, in vertical section and elevation shows a sufficient portion of a spooling machine with my improvements added to enable my invention to be understood. Fig. 2, is a detail showing the brake or lifting lever. Fig. 3, shows the tipping lever and its stand detached from the machine; and Fig. 4, a detail of the brake or lifting lever.

40 45 50 55 60 65 70 75 80 85 90 95 100

A represents a portion of the frame-work of a spooling machine; A' a cross rail, it, as herein shown, supporting a stand A² having suitable bearings for an intermediate roll A³, said stand also having guide wires 2 upon

which slides a suitable traverse guide h³, shown chiefly by dotted lines in Fig. 1, said traverse guide having suitable eye or eyes for the reception of the yarn y to be wound upon a suitable receiver a, a tube or cone, placed upon a roller having its journals held

in suitable bearings or notches of a yoke a' pivoted at a², said yoke having preferably co-operating with it a suitable friction device, as a³, to aid in keeping it in the position in which it is put by the accumulating mass of 55 yarn a⁴ being wound upon the yarn receiver. The rail or other suitable part of the framework has suitable bearings, not shown, for the shaft e', having as represented fast to it disks e surrounded by a driving drum h, said 60 driving drum in practice, having, as provided for in United States Patent No. 459,039, a crossing groove to receive the foot of a stud extended from the traverse device h³ into said groove, the groove causing the traverse device 65 to lay the yarn from end to end of the receiver, of whatever form.

As provided for in the patent last referred to, the driving drum, represented as a shell roll, hangs by its weight upon the disk e and 70 is rotated thereby, but the rotation of the roll may be stopped instantly by simply lifting it so as to break contact between it and the disk e. Preferably the roll A³, common to the said patent, will be interposed between the shell 75 roll and the mass of yarn being wound.

Depending from the cross-bar A' is a stand having a ratchet wheel 33, said ratchet wheel being common to United States Patent No. 404,831, granted to me June 11, 1889, it in 80 practice being fast on the shaft 34 which may be rotated, as provided for in the said patent, or in any other suitable manner. Depending also from the said cross-bar is a stand 3, upon which is pivoted at 4 a leg 5, said leg having 85 a suitable pivot 6 upon which is mounted a tipping lever 32. The outer end of the lever 32 has, as represented, a projection 7 which may be a rod, see Fig. 3, and immediately above the outer end of the tipping lever is 90 arranged a drop wire b which hangs on the yarn coming from a suitable spool B over suitable friction rollers b', b², b³, of any desired number. The frame-work has another stand C which supports a fulcrum C' for a 95 suitable brake or lifting lever C², said lever as herein represented, having a notch 8 and an incline 9, the latter shown by dotted lines Fig. 1, and a stop 10. The inner end of the tipping lever is somewhat heavier than its 100

outer end, so that the said end normally rests against the stop 10, as represented by full lines in Fig. 1.

When the yarn is unbroken the drop wire 5 is kept up, as shown by full lines in Fig. 1, but should the yarn break, the drop wire b drops, strikes the outer end of the tipping lever, turning it into its dotted line position, so that the continuously rotating ratchet wheel 10 33 strikes the inner end of the tipping lever and moves it, viewing Fig. 1, to the right, causing the lower end of the leg 5 to ride along the incline 9, thus turning the brake or 15 lifting lever C^2 about its fulcrum C' , causing the inner end of said lever, faced preferably with india-rubber or other pad as d , to act against the driving drum or shell and lift the same or check its rotation. The lower end of 20 the leg 5 after traveling up to the incline 9 enters the notch 8, and it thereafter acts as a locking device for the brake or lifting lever. The yarn having been mended between the friction rod b^3 and the traverse guide, there being but a very short stretch of yarn between 25 the two, and the drop wire having been again lifted and strung upon the yarn, the operator to start the machine will simply push down upon the outer end of the brake lever C^2 , it yet having limited amount of movement, and 30 in so doing will release the leg 5 from the notch 8 and let the shipping lever by its own gravity assume its full line position.

To increase the effectiveness of the brake lever, I have covered that portion of it which 35 contacts with the driving drum with a flexible substance as india-rubber or leather marked d , the said material being unsupported centrally, thus enabling the soft or yielding material d to adapt itself readily to the periphery of the roll.

Having described my invention, what I claim, and desire to secure by Letters Patent, is—

1. In a spooling machine, a brake or lifting lever, and a pivoted tipping lever parallel to 45 the brake or lifting lever, combined with a drop rod adapted to tip the tipping lever from its normal into its abnormal position, and a device to act directly upon the tipping lever in its abnormal position and move it to positively actuate said brake lever to check the rotation of the driving drum, substantially as described.

2. In a spooling machine, the shaft e' , its wheel e , the shell roll, a tipping lever, a vibratory leg on which it is pivoted, a drop wire, and means to engage and move the tipping lever when moved from its normal into its abnormal position by the falling of a drop wire, combined with a brake or lifting lever 60 acted upon by said leg to lift the shell roll, substantially as described.

3. In a spooling machine, a driving roll, a co-operating rotatable yarn receiver, a lifting lever, and a pivoted tipping lever parallel to 65 the lifting lever; combined with a drop rod adapted in its descent to strike against and tip the tipping lever from its normal into its abnormal position; and a device to act directly upon the tipping lever in its abnormal 70 position and move it to positively actuate said lifting lever to arrest the winding of the yarn upon the yarn receiver, substantially as described.

4. The driving roll, combined with the brake 75 lever having a soft or flexible face d unsupported centrally, to thus enable the said face to readily adapt itself to the periphery of the driving roll, substantially as described.

In testimony whereof I have signed my 80 name to this specification in the presence of two subscribing witnesses.

JOHN W. FOSTER.
